Int. Cl. D26—05

U.S. Cl. D48—23 A

FIG. 1

FIG. 2

FIG. 3

FIG. 1 is a perspective view of a ceiling mounted fluorescent fixture showing my design;

FIG. 2 is a bottom view of the fixture of FIG. 1; and

FIG. 3 is a side elevational view of the fixture of FIG. 1.

The opposite sides of the fixture are identical with the sides shown in FIGS. 1 and 3. The major sections of the side walls are light transmitting as in the bottom. The upper securing portion is opaque.

I claim:

The ornamental design for a ceiling mounted fluorescent light fixture, as shown and described.
